UNITED STATES PATENT OFFICE

GEORGE GROEN, OF EVERLY, IOWA

CHURN

Application filed September 27, 1927. Serial No. 222,317.

The object of my invention is to provide a very simple and inexpensive churn comprising a container having parts so constructed and arranged as to be adapted to be mounted 5 on an agitator shaft of certain type of washing machines, so that the washing machine power plant may be used for running the churn.

Although the invention is susceptible of a 10 variety of embodiments, it is unnecessary to fully describe and illustrate more than one in order to give a full understanding of the invention both from its structural and functional standpoints.

15 With these and other objects in view, my invention consists in the construction, arrangement and combination of the various parts of my device, whereby the objects contemplated are attained, as hereinafter more 20 fully set forth, pointed out in my claim, and illustrated in the accompanying drawings, in which:

Figure 1 shows a vertical, sectional view through a portion of a washing machine tub, 25 having installed therein a churn embodying my invention.

Figure 2 is a detail, sectional view taken on the line 2—2 of Figure 1; and

Figure 3 is an inverted, perspective view 30 of the metal cap at the top of the tub projecting upwardly into the churn.

In the drawings, I have shown portions of a tub of a washing machine of the kind with which my churn is adapted to be used. 35 The tub is indicated generally by the reference character 10. It has the supporting legs 12 and the hinged cover 14.

Projecting upwardly from the bottom of the tub at the center thereof is the agitator 40 shaft 16, having the squared upper end 16^a.

My improved churn consists of a container indicated at 18, which has generally the form of a cylinder with the bottom 20. At its center, the bottom has an opening, as indicated at 22, and a tube 24 extends from

around the opening 22 upwardly a substantial distance into the churn.

The shaft 16 is received in a sleeve 26 forming a part of the washing machine. The squared end 16^a of the shaft projects above 50 the sleeve 26.

I provide at the top of the tube 24 a cap 28 which slips over the top of the tube 24 and is welded or otherwise tightly secured thereto.

In the cap 28 is a horizontal partition 30, 55 in which is a square hole 32 adapted to fit over the squared end 16^a of the shaft 16.

In some washing machines, there projects upwardly from the bottom a sleeve 34 with a reduced upper extension 34^a. The tube 60 24 is of such size as to fit over the reduced extension 34^a. The tube 24 and cap 28 are strong enough to support the churn body 18 just above the bottom of the tub 10 of the washing machine. 65

The churn projects upwardly above the washing machine in the sizes most commonly used.

A hollow cone 36 surrounds the tube 24 at the lower part of the cone and is securely 70 fastened thereto as by welding, and rests upon and is fastened to the bottom 20 of the churn.

The cone 36 serves to brace and strengthen the tube 24 and also serves a function in contributing to the proper agitation of the cream 75 in the churn.

The churn is provided with one or more vanes or wings 40, which may be secured to the interior of the side wall of the churn and projected inwardly, or might be secured to the tube 24, as seems more desirable under the circumstances. 80

Near its upper end, the churn body 18 is 85 provided on opposite sides with suitable handles 42. The churn is provided with a cone-shaped top or cover 44, having a downwardly projecting annular flange 46, adapted to snugly enter the upper end of the churn 90

body 18. The cover 44 has a suitable, centrally arranged handle 48.

In the upper end of the cover is a downwardly projecting tube 50 serving as an air vent.

In the actual use of my improved churn, it is of course employed with the washing machine in the manner already described.

The agitator is removed from the washing machine, leaving the sleeve 26 and the shaft 16 projecting upwardly as shown.

The churn is inserted from above into the tub 10 with the tube 24 receiving the sleeve 26 and the shaft 16 until the squared end 16^a of the shaft enters the square hole 32 in the partition 30 of the cap 28. This cap, of course, is fastened to the tube 24 by a liquid tight joint.

When the washing machine motor or other power unit is set in motion, it will be remembered that the dolly shaft 16 has a reciprocating rotary movement on account of the connection of the squared end 16^a of the shaft with the cap 28.

This reciprocatory rotary movement is imparted to the churn.

There is thus provided a churn, which can be used by those who own the washing machines adapted for use with the churn.

For the purpose of observing the condition of the cream 38 in the churn 18, I provide a glass 54 suitably secured to the churn over an opening 56 in the side thereof. The condition of the cream 38 can thus be observed without the necessity of removing the cover 44 of the churn.

Such a churn can be built at a very modest expense, and can be operated from a power plant already provided without any additional expense for equipment.

Such a churn is therefore very economical to build and it is economical to operate.

Another advantage of a churn of this kind arises from the fact that water 52 can be placed in the tub 10 and maintained at the proper temperature for securing the best results in churning butter.

Changes may be made in the details of the construction and arrangement of the parts of my improved churn without departing from the real spirit and purpose of my invention, and it is my intention to cover by my claim any modified forms of structure or use of mechanical equivalents, which may be reasonably included within the scope of such claim.

I claim as my invention:

For use with a washing machine having a tub and an oscillatably mounted shaft extending upwardly from the bottom thereof through a stationary sleeve for normally supporting a washing dolly, a churn of the character disclosed comprising a cylindrical container provided with a sleeve extending upwardly from and connected with the bot-

tom of the container and adapted to fit over the sleeve of the washing machine, a cap on the sleeve of the churn having means operatively cooperating with said shaft, blades in said container and a hollow truncated cone member therein surrounding the sleeve and extending upwardly and inwardly from the bottom thereof for bracing the sleeve of the churn relative to the bottom thereof.

Des Moines, Iowa, September 19, 1927. 75
GEORGE GROEN.
